UNITED STATES PATENT OFFICE.

WILLIAM R. LAMPTON, OF TERRE HAUTE, INDIANA, ASSIGNOR OF ONE-HALF TO WILLIS O. WINN, OF SAME PLACE.

DEVICE FOR CONVERTING MOTION.

SPECIFICATION forming part of Letters Patent No. 293,477, dated February 12, 1884.

Application filed January 11, 1884. (No model.)

To all whom it may concern:

Be it known that I, WILLIAM R. LAMPTON, of Terre Haute, in the county of Vigo and State of Indiana, have invented certain new and useful Improvements in Mechanical Movements or Devices for Converting Motion; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in mechanical movements or devices for converting motion, whereby without jar or shock a smooth, steady, and even motion is given to the working parts. In the accompanying drawings I have illustrated my improved movement as applied to the cutter-bar of a mowing-machine; but I do not restrict myself to its use in such connection, as it is equally applicable to all machines in which reciprocating motion in a right line is to be given to one of the working parts.

Referring to the separate figures, in which like letters indicate like parts, Figure 1 is a plan view of a mowing-machine to which my invention may be applied. Fig. 2 is a similar view of a part thereof upon an enlarged scale. Fig. 3 is an end view taken on the line *x x*, Fig. 2.

The shaft *A*, carrying an outer cog-wheel, which is connected by suitable gearing to the source of power, is rotated in suitable bearings upon the frame-work of the machine. At its inner end the shaft is provided with a fixed triangular cam of the peculiar form shown in the drawings. The cam revolves between friction-rollers *B C*, supported on brackets *E E*, attached to the cutter-bar. The centers of the cam-shaft and friction-roller axles are upon the same line in a single horizontal plane, and the distance between the rollers themselves is that measured by a straight line passing from one of the cam-points through the center of the shaft and terminating at the opposite cam-edge. When the cam is in the position shown in Fig. 3, (one point touching

the roller *B* and the opposite concave, the roller *C*), the throw of the cam in the direction of the roller *B* can be determined by subtracting the distances between the center of the shaft and the points of contact from each other. 55 The throw toward the roller *C* is the same. The cam is hollowed out or concave upon each of its sides. The terminal points are, however, substantially sharp, and between them the concaves have the sides curved in an opposite direction, as shown. This peculiar shaping of the cam is attended with great advantages in the smooth operation of the machine, and, in connection with the bracketed friction-rollers, insures a more rapid change of 60 motion without wear or jar than any other with which I am acquainted. In my cam-motion there is practically no dead-point, as there would be if the cam were rounded at its ends. The sharply-pointed ends of my cam 70 permit and insure an instantaneous change in the direction of the throw the moment such point has passed the center of the friction-roller. Thus supposing the cam to be revolving from left to right with reference to Fig. 3: 75 At the beginning of this movement the point 3 moves instantly below the center line of the shaft and rollers, allowing instantaneous movement of the cutter-bar. If the cam were merely curved, instead of being pointed, as in my 80 construction, there would be a certain time in which starting from the position of Fig. 3 no motion whatever would be imparted to the cutter-bar, which would be a serious disadvantage. If the sides of the cam, on the other 85 hand, were made merely straight or concave, and terminating in points, at each change of movement of the cutter-bar there would be a sudden shock or jerk caused by the too-rapid movements of the friction-roller *C* along the 90 side 2 3. By giving my cam an outward curve or convex on each side of the points, I avoid 95 this difficulty, as the tendency to a sudden slipping along the face of the cam is obviated by the slight resistance offered by the convex at the beginning of the movement, while, as above stated, the sharp points permit an instantaneous change in the motion of the cutter-bar when the cam has reached the outer limit of its throw. In this way my cam ob: 100

viates all the disadvantages of the old forms, while possessing all their superior qualities. The easy continuous movement of the parts is greatly assisted by the friction-rollers, which 5 also prevent wearing off of the points of the cam.

Having thus described my invention, what I claim, and desire to secure by Letters Patent, is—

10 In a machine driven by either cog or belt gearing, a mechanical movement or device for converting motion, consisting of the combination, with the loosely-journalized shaft-bearing,

cam shaped, as described, of the bracketed friction-rollers on and in combination with 15 the reciprocating bar, whereby a continuous, steady, and even rectilinear motion is imparted thereto, substantially as described.

In testimony that I claim the foregoing as my own I affix my signature in presence of two witnesses.

WILLIAM R. LAMPTON.

Witnesses:

JOHN C. PENNIE,
EDWARD E. ELLIS.

Correction in Letters Patent No. 293,477.

It is hereby certified that in Letters Patent No. 293,477, granted February 12, 1884, upon the application of William R. Lampton, of Terre Haute, Indiana, for an improvement in "Devices for Converting Motion," the claim was improperly punctuated in the printing thereof, whereby the meaning and intent were changed. Said claim should be read as follows to make the Letters Patent conform to the record of the case in the Patent Office, viz:

"In a machine driven by either cog or belt gearing, a mechanical movement or device for converting motion, consisting of the combination, with the loosely-journaled shaft, bearing cam shaped as described, of the bracketed friction-rollers on and in combination with the reciprocating bar, whereby a continuous, steady, and even rectilinear motion is imparted thereto, substantially as described."

Signed, countersigned, and sealed this 19th day of February, A. D. 1884.

[SEAL.]

M. L. JOSLYN,
Acting Secretary of the Interior.

Countersigned:

BENJ. BUTTERWORTH,
Commissioner of Patents.
